CLAIM

(21) Appl. No.: **29/277,176**

The ornamental design for a "sprayer head for attachment to a bottle," as shown and described

(22) Filed: **Feb. 16, 2007**

DESCRIPTION

(51) **LOC (8) Cl.** **09-07**

FIG. 1 is a perspective view showing a sprayer head for attachment to a bottle;

(52) **U.S. Cl.** **D9/448**

FIG. 2 is a front view of the sprayer head of FIG. 1;

(58) **Field of Classification Search** D9/686, D9/685, 682, 448, 447; 239/333; 222/383.2, 222/383.1, 340; D23/226

FIG. 3 is a left side view of the sprayer head of FIG. 1;

See application file for complete search history.

FIG. 4 is a rear view of the sprayer head of FIG. 1; and, FIG. 5 is a right side view of the sprayer head of FIG. 1; and, FIG. 6 is a top view of the sprayer head of FIG. 1.

(56) **References Cited**

The broken lines showing a bottle appearing in FIGS. 1–6; the broken lines showing a trigger in FIGS. 1–3 and 5; the broken lines showing a central aperture and screw-top fastener in FIGS. 1–5; the broken lines showing a seam between two halves of the sprayer head in FIGS. 1–2, 4, and 6; the broken lines showing circular apertures for fastening two halves of the sprayer head together in FIGS. 1–4 and 6; and the broken lines showing a outlet in a nozzle of the sprayer head in FIGS. 1–2; are for the purpose of illustration only, and form no part of the claimed design
